US0D1088358S

(12) **United States Design Patent** (10) **Patent No.:** **US D1,088,358 S**
(45) **Date of Patent:** **** Aug. 12, 2025**

(54) **DESCENT CONTROLLER HOUSING**

(71) Applicant: **Tech Safety Lines, Inc.**, Carrollton, TX (US)

(72) Inventor: **Johnny Dickson**, Van Alstyne, TX (US)

(73) Assignee: **Tech Safety Lines, Inc.**, Carrollton, TX (US)

(**) Term: **15 Years**

(21) Appl. No.: **29/793,669**

(22) Filed: **Jan. 10, 2024**

Related U.S. Application Data

(63) Continuation-in-part of application No. 18/104,854, filed on Feb. 2, 2023, now Pat. No. 11,998,768, and (Continued)

(57) **CLAIM**

The ornamental design for a descent controller housing as shown and described herein.

DESCRIPTION

FIG. 1 is a front perspective view of the descent controller housing;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof; and,

FIG. 7 is a bottom view thereof.

The broken lines depict portions of the descent controller housing that form no part of the claimed design.

1 Claim, 4 Drawing Sheets

Related U.S. Application Data

a continuation-in-part of application No. 17/174,928, filed on Feb. 12, 2021, now Pat. No. 11,752,366, which is a continuation of application No. 16/850,556, filed on Apr. 16, 2020, now Pat. No. 10,918,892, which is a continuation-in-part of application No. 29/709,731, filed on Oct. 16, 2019, now Pat. No. Des. 957,743, and a continuation-in-part of application No. 29/709,729, filed on Oct. 16, 2019, now Pat. No. Des. 933,308, and a continuation-in-part of application No. 29/709,730, filed on Oct. 16, 2019, now Pat. No. Des. 957,742.
